H. W. STROUT.
BILGE WATER PUMPING DEVICE.
APPLICATION FILED MAR. 31, 1913.

Patented May 26, 1914.

UNITED STATES PATENT OFFICE.

HARRY WINGATE STROUT, OF HAVERHILL, MASSACHUSETTS.

BILGE-WATER-PUMPING DEVICE.

1,097,890.

Specification of Letters Patent. Patented May 26, 1914.

Application filed March 31, 1913. Serial No. 757,882.

To all whom it may concern:

Be it known that I, HARRY W. STROUT, a citizen of the United States, residing at Haverhill, county of Essex, and State of Massachusetts, have invented certain new and useful Improvements in Bilge-Water-Pumping Devices, of which the following is a specification.

My invention relates to devices for pumping water from the bottoms of boats and particularly to a device of the character mentioned especially adapted for use upon small motor boats.

The object of my invention is to provide a device of the class mentioned operable by the current of air produced either by the motion of the boat or by the wind to keep the bilge water pumped from the boat.

A further object of my invention is to provide a device as mentioned which shall be automatically set in operation by the accumulation of water in the boat and automatically stopped when the water has been removed.

A further object of my invention is to provide a mounting for the device whereby the same may be readily adjusted to a proper vertical position irrespective of the slant of the deck or part to which it is secured.

A further object of my invention is to provide a device of the class under consideration which shall be ornamental when applied to the boat and which shall also serve as a flag staff.

Other objects will appear hereinafter.

With these objects in view my invention consists generally in a base adapted to be secured to the boat, a standard mounted thereon, a pump at the lower end of said standard, a wind mill at the upper end thereof and a connection between the wind mill and the pump.

My invention further consists in a device characterized as above stated equipped with a brake mechanism for the wind mill, a float and a connection between the float and the brake whereby the operation of the wind mill is controlled by the rise or fall of water within the boat.

My invention further consists in a device as stated further characterized by an adjustable connection between the base and the standard whereby the latter may be secured in vertical position irrespective of the inclination of the portion of the boat to which the base is secured.

My invention further consists in various details of construction and arrangements of parts all as will be fully described herein-after and particularly pointed out in the claims.

My invention will be more readily understood by reference to the accompanying drawings forming a part of this specification and in which—

Figure 1 is a side elevation partially in section of a bilge water pumping mechanism embodying my invention in its preferred form and illustrating the same in position on a small boat, a portion of the latter being illustrated diagrammatically, Fig. 2 is a detail view, and Fig. 3 is a side elevation of a modified form of the device.

Referring now to the drawings 1 indicates a portion of the hull of a boat and 2 the deck thereof at or adjacent the bow, at which point I prefer to arrange my improved device. Secured to the deck 2 is a base casting 3 formed with a clamp socket 4.

5 indicates a standard. This is preferably formed of a length of brass tubing and is provided intermediate its ends with an enlarged ball portion 6 fitting within the socket 4 of the base casting 3. It is obvious that by this construction the standard may be arranged in vertical position irrespective of the slant or inclination of the base. The standard 5 extends below the base 3 and is provided at the lower end with a pump 7 preferably of the double ball type as shown but it is obvious that any suitable pump may be employed in the combination. The pump is provided with a flexible discharge pipe 8.

Secured to the upper end of the standard 5 is a casting 9 provided with bearings 10 for a horizontal shaft 11 upon one end of which is mounted the wind mill vanes 12.

Arranged within the standard 5 is the pump rod 13 provided at its upper end with a transversely enlarged portion 14 formed with a horizontal slot 15, and the inner end of the shaft 11 is provided with a crank pin 16 extending into the slot 15, by which construction the rotary motion of the wind mill 100 is transformed into a reciprocating motion in the rod 13.

The device is particularly adapted for use upon motor boats and it is obvious that when the boat is under way the wind mill 110 will be set in operation by the current of air produced by the motion of the boat.

However, if the boat is traveling at an angle to the wind the device may be shifted so that the wind mill may face the current of air, the ball and socket connection between 5 the base and standard permitting of such adjustment. It should be understood that such adjustment is seldom necessary.

In order that the wind mill and pump shall operate only when there is water to be 10 pumped, I provide a suitable brake mechanism.

17 indicates a disk fixed to the shaft 11 and pivoted upon the casting 9 as a lever 18 provided with a brake shoe 19 adapted to 15 engage the periphery of the disk 17. The lever 18 is connected by a rod 20 to a lever 21 pivotally connected at one end to the pump 7 or adjacent thereto and provided at the other end with a float 22. Any accumulation of water in the boat will raise the 20 float 22 and release the brake 19 and when the float and arm 21 drop to normal position the brake is applied to the wind mill. If preferred an annular float 23 may be provided 25 surrounding the cylinder of the pump 7 as shown clearly in Fig. 3 and this connected by the rod 20 to the brake shoe 19.

24 indicates a block secured to the casting 9 for flag halyards 25 and a cleat 26 is

formed upon the base 3 to secure the 30 halyards.

Having described my invention, I claim:

1. In a device of the class described, a base adapted to be secured to a boat, a tubular standard, a ball and socket connection 35 between said base and said standard, a pump at the lower end of said standard, a wind mill at the upper end of said standard and a rod connecting said mill and said pump, substantially as described.

40
2. In a device of the class described, a base provided with a clamp socket, a tubular standard provided intermediate its ends with a ball arranged within said socket a pump on the lower end of said standard, a wind mill at the upper end thereof, a pump rod in said standard and connecting said pump and said mill, brake mechanism for 45 said wind mill, a float adjacent said pump and a rod connecting said brake and said 50 float, substantially as described.

In testimony whereof I have signed my name to this specification in the presence of two subscribing witnesses.

HARRY WINGATE STROUT.
